(57) **CLAIM**

The ornamental design for a geometrical speaker enclosure, as shown and described.

DESCRIPTION

FIG. 1 is a front left perspective view of a geometrical speaker enclosure showing my new design;

FIG. 2 is an alternative front perspective view thereof;

FIG. 3 is a rear perspective view thereof;

FIG. 4 is a left side perspective view thereof;

FIG. 5 is a right side perspective view thereof;

FIG. 6 is a top, front perspective view thereof; and,

FIG. 7 is a bottom perspective view thereof.

In the drawings, the broken lines depict portion of the geometrical speaker enclosure that form no part of the claimed design.
